(57) CLAIM

The ornamental design for an air rifle, as shown and described.

DESCRIPTION

FIG. 1 is a right side elevation view of the air rifle, showing my new design;

FIG. 2 is a left side elevation view of the air rifle;

FIG. 3 is a top plan view of the air rifle;

FIG. 4 is a bottom plan view of the air rifle;

FIG. 5 is a front elevation view of the air rifle; and,

FIG. 6 is a rear view of the air rifle.

The portions of the air rifle shown in broken lines form no part of the claimed design.
